C. N. WERNITZ,
ARTIST'S COLOR BOX,
APPLICATION FILED MAY 2, 1919.

1,391,028.

Patented Sept. 20, 1921.

Inventor:
Carl N. Werntz
By Cheever & Co.
Atty.

UNITED STATES PATENT OFFICE.

CARL N. WERNTZ, OF CHICAGO, ILLINOIS.

ARTIST'S COLOR-BOX.

1,391,028.

Specification of Letters Patent. Patented Sept. 20, 1921.

Application filed May 2, 1919. Serial No. 294,305.

To all whom it may concern:

Be it known that I, CARL N. WERNTZ, a citizen of the United States, residing at Chicago, in the county of Cook and State of Illinois, have invented a certain new and useful Improvement in Artists' Color-Boxes, of which the following is a specification.

This invention relates to artists' tools and equipment and particularly to means for carrying different pigments required by the artist.

The objects of the invention are to provide a color box which is mechanically very compact in form, easily and cheaply made, satisfactory in use and not liable to get out of order in which the cover for the box proper constitutes when inverted a convenient water bowl, and in which the locking devices for securing the cover on the box form when swung to different positions, handles for carrying the open color box proper or a leg or legs for supporting the box from an inclined desk or the like so as to maintain the box substantially level notwithstanding the inclination of the desk.

A further and very important object of the invention is to so arrange the colors in the box that, regardless of its specific form, an artist of medium ability can by simply applying the colors in the order of their arrangement in the box produce in the picture predetermined desired results.

The invention consists in means for carrying out the foregoing and other objects and in features and details of construction hereafter more fully set forth in the specifications and claims.

Referring to the drawing, in which similar numerals represent the same parts throughout the several views,

Fig. 1 is a perspective view of mechanism of this invention in its preferred form, the handles being in the position for supporting the box upon an inclined desk.

Fig. 2 is a vertical section detail view through the center of the device in the position in which all the parts assume when they are folded together ready for carrying in the hand for shipment.

Fig. 3 is a perspective view of the cover removed from other part of the device then used as a water bowl or the like.

Fig. 4 is a somewhat reduced perspective

view of the device when assembled as shown in Fig. 2.

Mechanically speaking, the device comprises a color carrier member made preferably from a flat plate of suitable metal 10 bent in a stamping machine so as to form a vertical circular depending flange 12 and a 60 plurality of superficial paint receptacles 14 arranged about the center of the plate and divided substantially equally on opposite sides of an elongated brush receptacle 16 adapted to contain the brush 18. Each 65 paint receptacle 14 communicates through a relatively shallow passageway 20 with a deeper and enlarged mixing chamber or well 70 for the particular paint color in the adjacent paint receptacle. The paint mixing wells 75 are for convenience hereafter, numbered 21, 22, 23, 24, 25 and 26 on one side of the brush receptacle, and 31, 32, 33, 34, 35 and 36 on the other side of the brush receptacle, there being in the preferred form of the device exactly six such receptacles on opposite sides of a given line, which in the form of the device here shown, happens to be the brush receptacle, but which might be defined in any other way without departing from this invention.

The parts thus far described are normally closed and covered by an inverted bowl 38 held in place as a cover member by wire handles 40 and 41 suitably pivoted in any suitable manner to the bottom edge 42 of downwardly turned flange 12, the details forming no part of this invention, the only requirement being that the joint or hinge for the handles shall be made tight enough so that 80 the handles will readily stay in any of the positions shown in the drawings until manually moved therefrom. In the positions of Figs. 2 and 4 the handles hold the cover in place on the color box in the position shown in Fig. 1; handle 40 is in the position where it holds the front edge of the box, as viewed in the drawings up from an inclined desk so that the top plate 10 of the color box is level or near enough so for practical purposes.

In the mechanical manipulation of the device the operator carries the box about with everything assembled as shown in Fig. 2. When he gets where work is to be done, he simply moves the handles 40 and 41 either 105 to the position of Fig. 1 or some other de-

sired position, removes cover 38 and proceeds with his painting, in so doing using the bowl 38 as a general purpose water receptacle. When he gets through he merely empties the 5 water out of bowl 38, inverts it, puts it in place on the color box and snaps the handle 40 and 41 to the position of Figs. 2 and 4. The indentation 44 in the bowl serves the function of closely engaging the brush 18 as 10 shown in Fig. 2 to hold it in place.

In the artistic feature of the invention as exemplified in this box, the color receptacles 14 belonging to the respective mixing wells are charged as follows:

- 15 21, yellow green,
- 22, yellow,
- 23, orange yellow,
- 24, orange,
- 25, red orange,
- 20 26, red,
- 31, green,
- 32, blue green,
- 33, blue,
- 34, blue-purple,
- 25 35, purple,
- 36, red purple.

When charged in this way the first six are warm colors and the lower six are cool colors.

30 In painting in colors the problem for the student to solve is what colors to use in painting the lights and the shadows under varying conditions. In painting a sunlight effect the artist must, in painting the lights, 35 use some or all of the colors heretofore set forth in the warm section of the box and in painting the shadows for said sunlight effect he must use one or all of the colors set forth in the second or cool color section of the 40 box. On the contrary, in indoor painting, where sunlight is not involved, the situation is reversed; the lights must be painted with one or more of the colors in the cool color section of the box and the indoor shadows 45 must be painted with one or more of the colors from the warm color section of the box. The result of this situation is that a student, being once given the simple formula just set forth and a box equipped in accordance with 50 this invention cannot go very far wrong in making his picture. While the device is of great value for the student, it is of almost equal value to the greatest artist because it automatically prevents him from becoming 55 accidentally mixed as to the color he is applying.

The twelve colors in the box are arranged so that opposite colors *i. e.*, colors on opposite diameters of the box are complementary to each other, with the result that a designer having to make a design requiring a harmony of warm colors, can by the use of the device of this invention make his design 60 from the warm color section of the box as 65 he may elect, and contrast such colors by the

use of the exact complementary colors therefor by simply traveling along the diameters of the box from the warm colors used to the complementary colors.

Having thus described my invention what 70 I claim as new and desire to secure by Letters Patent, is:—

1. A color box having on its working surface a plurality of paint receptacles and their correlated larger mixing wells so arranged that when half of the receptacles are stocked with warm colors and the other half are stocked with cool colors, each group is on one side of a given line and the complementary colors in each group are opposite 80 each other.

2. A color box having on its working surface a plurality of paint receptacles and their correlated larger outwardly disposed mixing wells so arranged that when half of 85 the receptacles are stocked with warm colors and the other half are stocked with cool colors each group is on one side of a given line defined by a brush receptacle and the complementary colors in each group are opposite 90 each other.

3. In mechanism of the class described a plate having a plurality of paint receptacles and the coöperating mixing wells arranged in two distinct groups on opposite 95 sides of a central line and so arranged that complementary colors can be placed in receptacles diametrically opposite each other across said line and across a common center.

4. In mechanism of the class described 100 a plate having a plurality of paint receptacles and the coöperating mixing wells arranged in two distinct groups on opposite sides of a central line about a common center and so arranged that complementary colors 105 can be placed in receptacles diametrically opposite each other across said line.

5. In mechanism of the class described a circular plate having a plurality of radially disposed paint receptacles, each provided 110 with an outwardly placed coöperating mixing well, arranged in two distinct groups on opposite sides of a clearly defined central line and so arranged that complementary colors can be placed in receptacles diametrically 115 opposite each other across said line.

6. In mechanism of the class described a circular plate having a plurality of radially disposed paint receptacles, each provided with an outwardly placed larger coöperating mixing well; arranged in two distinct groups on opposite sides of a central line defined by a brush receptacle formed in the plate across the plate over its center and so arranged that complementary colors can be 125 placed in receptacles diametrically opposite each other across said line and the center of the plate.

7. In combination with a plate, having 130 color compartments therein, and supported

by a down turned flange, a cover in the form of an invertible dish fitting over said plate and down said flange and means for securing the cover in place.

- 5 8. In combination with a plate, having color compartments therein, and supported by a down turned flange, a cover in the form of an invertible dish fitting over said plate and down said flange and leg members pivoted to the outer edge of said flange swingable to two positions in one of which they

hold the cover in place on the box in the other of which they jointly or severally support the device up from a desk or a table.

In witness whereof, I have hereunto subscribed my name in the presence of two witnesses.

CARL N. WERNZ.
